UNITED STATES PATENT OFFICE.

AMANDUS J. KIRKPATRICK, OF ALTOONA, PENNSYLVANIA.

BURGLAR-PROOF STRUCTURE.

1,330,475.

Specification of Letters Patent. Patented Feb. 10, 1920.

Application filed July 10, 1919. Serial No. 309,953.

To all whom it may concern:

Be it known that I, AMANDUS J. KIRKPATRICK, a citizen of the United States, residing at Altoona, in the county of Blair and State of Pennsylvania, have invented certain new and useful Improvements in Burglar-Proof Structures, of which the following is a specification.

This invention relates to express cars, and more especially to those wherein the structure is known as burglar-proof; and the object of the same is to provide an apartment for erection within such car, which will protect the valuables and which may serve also for protection for the express agent when he enters the same. It will be stated here that it is quite possible to erect this structure in banks, in counting houses, and in various places where valuables are to be stored or transported, and therefore, while illustrated and described as part of an express car, the invention should not be thus limited in its use.

Besides the broad object thus stated, the invention includes a peculiar form of wall to prevent the glancing of bullets which might injure other railway employees than the agent, a wall externally camouflaged and pierced at intervals with port holes protected by internal shields or plates and through which the agent may fire from the interior, a structure which overhangs the entrance door after the fashion of a block house and has openings through which the agent can fire from above, and other details more fully set forth in the following specification and claims.

Referring to the drawings:

Figure 1 is a perspective view illustrating the body of a car broken away to show this structure erected within its interior.

Figs. 2 and 3 are enlarged sections on the lines 2-2 and 3-3 of Fig. 1, and Fig. 4 is a section on the line 4-4 of Fig. 3, all showing the structure only.

The car C may have a floor F and wall W of pressed steel, as express cars are now often made, and similarly the parts of a building within which this improved structure is used may be of metal, stone or brick, or other material which is proof against burglars and highwaymen, at least in the limited time in which they have to operate. Also such walls may be and usually are fire-proof. When this improved structure is built upon the floor F and against the wall

W of a building or a car C as shown in Fig. 1, it need not necessarily have a floor and a rear wall. If built in a corner two walls may be omitted, and if carried up to the ceiling its top may be omitted, as the corresponding parts of the building or car take the place of these elements because the structure will be connected with said parts firmly. The following description must therefore be read with this idea in view, where the structure will have no rear wall, although the remaining views show it with a rear wall and a top and bottom so that it is a complete unit.

Broadly speaking the structure comprises two sides, 1 and 2, and a rear wall 3 rising from a floor 4 to a top 5, the upper portion of the sides being carried forward into an overhang having a floor 6 of its own and the top being correspondingly extended, and this overhang having a front wall 7. The entrance door is inset to the inner edge of the floor 6, and is broadly indicated at 8. The rear wall 3 would be omitted in Fig. 1, and possibly the floor 4, and the top 5 might be omitted if the structure were extended to the roof R of the car, or the structure might be built into the corner of the car and its rear wall and one of the sides omitted. Of course the door could face either transversely or longitudinally of the car, or, by appropriate modification, it might be possible to erect the structure across a corner of the car or building and have its door face obliquely. The floor 4 may have strips 14 standing on edge and constituting joists of its own, which would probably be the construction if the car floor F were of wood, and thus the metal floor 4 would protect the interior of the structure from being reached from the bottom. Appropriate angle irons 10 form the sills for the floor, and other angle irons 11 may form the uprights at the corners, metal strips 12 being provided at intervals extending horizontally past the uprights and bolted thereto as at 13. Other strips 15 will connect the upper ends of the uprights, angle iron elements being used where possible, and thus a skeleton frame work structure is built up which is light and strong. Surrounding this structure is a sheathing 16 of sheet metal forming the walls and the top and floor and bolted or riveted to the frame work in a manner which will be clear. Next outside the sheathing on all or most of the

upright walls are strips 17 of wood or metal or appropriate material, preferably overlying the strips and the uprights of the framework and held by the same fasteners 13. 5 Next outside these strips 17 is a facing 18 which may be of quite light material, such as tin, tongue-and-groove lumber, paper, or preferably compo board, also held to the strips by the same fasteners 13 or possibly 10 tacked to the strips 17 if the latter be of wood. This structure is shown as prevailing in the rear wall 3 of Fig. 1 and is omitted from the front wall 7 of Fig. 3, but it should exist on most or all of the exposed 15 side walls. Its purpose is, without materially increasing the weight, to produce a wall having a small vertical space between its sheathing and its facing, the width of the space depending upon the thickness of 20 the strips 17. When a robbery occurs and the highwaymen fire at this structure, the bullet will penetrate the facing but will not penetrate the sheathing as the latter must be made sufficiently heavy to be bullet-proof, 25 and the result will be that the bullet will pass through the facing but will not glance off the sheathing to the possible injury of other employees standing within the car, the bullet simply falling within said space 30 and coming to rest upon one of the strips 17, or in other words, it will be pocketed within the hollow wall structure. It is quite within the spirit of the invention, however, to make both sheets of the wall of metal if 35 desired, and also to construct the door 8 in the same way if preferred, although the front wall 7 being rather high need not necessarily have this construction unless it is desired.

40 The door 8 may be single or double, according to the width of the structure, and while it may be a sliding or a hinged door as the manufacturer desires, it is illustrated herein as hinged at one side at 20 to one 45 of the uprights 21 of a door frame so that it may be closed against the opposite upright 22, a cross strip 23 at the top, and a sill 10 at the bottom, and it is shown as capable of being fastened from the interior 50 by means of a cross bar 24 centrally pivoted at 25 and having an operating handle 26, the ends of the bar turning behind keepers 27 and 28 on the uprights 21 and 22 to firmly 55 lock the door closed.

55 The exposed walls of the structure are preferably painted or otherwise camouflaged with rings or circles as seen at 30 in Fig. 1, and certain of these are opposite holes 38 in the facing which in turn are 60 opposite holes 36 in the sheathing, thereby producing a port hole which is hardly discernible from the exterior. A port hole 37 is purposely formed in the floor 6 of the overhang, the same being covered by a plate 65 31 pivoted at 32 and having a handle 33 so

that it may be turned aside by the operator on the interior. Similar plates 34 are pivotally mounted within the double walls to close the other holes and therefore protect the agent on the interior. Although not so 70 shown, it is possible that the door might have such an opening, but it is preferred not, and the material of the door should be heavier than that elsewhere used.

Assuming that such a structure is erected 75 within an express car C, and train robbers hold up the train and gain admittance through the windows or doors of the car and threaten the agent. He will immediately run into this burglar-proof structure, 80 wherein of course his most highly valuable packages will be stored, and close and lock the door behind him, leaving the robbers on the exterior although they are within the car. In their chagrin at being thus baffled, 85 they will doubtless fire at the structure with the hope of wrecking it and of intimidating or killing the agent. It has been shown how bullets striking the side walls will be pocketed, rather than glancing off to the injury 90 of others within the car. If the door 8 be made of extra heavy metal, bullets fired point blank at it, or the efforts of the robbers to smash it in, will be effectually withstood. Meanwhile the agent can turn aside any of 95 the plates or shields and fire from the interior upon the intruders. Undoubtedly their main efforts will be directed toward opening or smashing in the door 8, and hence the utility of the overhang with the hole 100 37 in its floor is apparent. Also the painting of the facing with camouflage as indicated at 30 will prevent the highwaymen from ascertaining the location of the portholes through which the defensive shots come. 105 Taking into consideration the limited time in which the robbers must act, it is believed that a structure of this kind will enable the agent to hold them off at least until assistance arrives, and of course the noise of the 110 fusillade would attract attention even if this structure were in a building and the attack was made in the dead of the night.

It has not been thought necessary to amplify details to the extent of showing 115 an ordinary lock with which the door may be provided so that it may be closed and locked from the exterior and thus serve as a safe, nor shelving or other means on the interior for the storage of express packages 120 and the like, nor the means for lighting the interior of the structure. This specification is confined to those features necessarily forming part of the invention, and modifications are contemplated within the spirit 125 of the appended claims, bearing in mind that the element herein called a car C might be a building within which the structure is set up, and to whose walls and floor and ceiling its parts will of course be securely at- 130

tached. Finally it is also quite within the spirit of the invention to fire proof the walls, but details are omitted.

Having thus described the invention, what is claimed as new is:

1. The herein described burglar-proof structure, including an entrance door inset from the front edges of its side walls to produce an overhang, a floor for the overhang above the door opening, the floor having a hole and means for locking the door from the interior.

2. The herein described burglar-proof structure including an entrance door inset from the front edges of its side walls to produce an overhang, a floor for the overhang above the door opening, the floor having a hole, a guard movable over said hole and having a handle on the interior of the overhang, and means for locking the door from the interior.

3. The herein described burglar-proof structure including an entrance door with means for locking it from the interior, and walls camouflaged exteriorly in spots and perforated through certain of the spots, and guards movably mounted upon the interior over said perforations.

4. In a burglar-proof structure, a wall composed of a bullet-proof sheathing, strips on the exterior thereof, and a facing secured upon the strips and leaving a pocket between

it and the sheathing, for the purpose set forth.

5. In a burglar-proof structure, a skeleton frame work adapted to be secured to a floor against the wall of a building or car, a bullet-proof door hinged in one of the exposed sides of said frame work and having means for fastening it from the interior, bullet-proof walls covering the remaining exposed sides of the frame work, certain of said walls having port holes and the structure having an overhang projecting beyond the door opening, the floor of the overhang having an opening, and guards movable over said port holes and operable from the interior of the structure.

6. In a fire-proof structure, the combination with a skeleton frame work composed of bars and strips and sills, certain of said elements defining a door frame and the frame work carried forward of and over the frame into an overhang, wall plates secured to said frame work with the side walls extending past the door frame, and floor plates in the overhang and on said sills; of a door hinged to one side bar of the frame, a cross bar centrally pivoted on the interior of the door, and keepers on the side bars of the frame with which the ends of said cross bar may be engaged, as described.

In testimony whereof I affix my signature.
AMANDUS J. KIRKPATRICK. [L. S.]
